DESIGN FOR A LOCKER LIFT HANDLE

Roy A. Stone and Carl W. Carlson, Rockford, Ill.,
assignors to National Lock Company, Rockford,
Ill., a corporation of Delaware

Application June 22, 1944, Serial No. 114,131

Term of patent 7 years

(Cl. D10—8)

To all whom it may concern:

Be it known that we, Roy A. Stone and Carl W. Carlson, citizens of the United States, residing at Rockford, in the county of Winnebago and State of Illinois, respectively, have invented a new, original, and ornamental Design for Locker Lift Handle, of which the following is a specification, reference being had to the accompanying drawing, forming part thereof.

In the drawing,

Fig. 1 is a side elevation of a locker lift handle embodying our new design;

Fig. 2 is a front elevation thereof;
Fig. 3 is an end view thereof looking down at Fig. 1;

Fig. 4 is an end view thereof looking up at Fig. 1; and

Fig. 5 is a sectional view on the line 5—5 of Fig. 1.

We claim:

The ornamental design for a locker lift handle, substantially as shown.

ROY A. STONE.
CARL W. CARLSON.
